UNITED STATES PATENT OFFICE.

DANIEL SMITH BAIRD, OF TORONTO, ONTARIO, CANADA, ASSIGNOR TO THE BUSINESS SYSTEMS LIMITED, OF TORONTO, CANADA, A CORPORATION OF CANADA.

LOOSE-LEAF BINDER.

No. 854,622.

Specification of Letters Patent.

Patented May 21, 1907.

Application filed June 20, 1906. Serial No. 322,624.

To all whom it may concern:

Be it known that I, DANIEL SMITH BAIRD, of the city of Toronto, in the county of York and Province of Ontario, Canada, have invented certain new and useful Improvements in Loose-Leaf Binders; and I hereby declare that the following is a full, clear, and exact description of the same.

This invention relates to a loose leaf binder comprising in its construction a binder back consisting of a middle member, two side members located at opposite sides of the middle member, an operating screw mounted in bearings connected to the inner face of the middle member, two wrist plates pivoted within the binder back, a slide-nut movable on the operating screw, a link connected with the wrist plates and intermediate the wrist plates with the slide-nut whereby it will oscillate the wrist plates during the movement of the slide-nut, and two sets of links having their inner ends pivotally connected to the wrist plates on lines passing through the wrist plate pivots transversely to the length of the operating screw and on opposite sides of and at the same distance therefrom, and having their outer ends pivotally connected to the side members on lines passing diametrically through the wrist plate pivots at substantially right angles to the length of the operating screw whereby the links of each set may move in substantially parallel planes during the oscillation of the wrist plates and during said movement constantly exert their lines of force on the side members at substantially right angles to the length of the operating screw as hereinafter set forth and particularly pointed out in the appended claims.

In the drawings: Figure 1 is a perspective view of a loose leaf binder showing the parts in their expanded positions. Fig. 2 is a similar view to Fig. 1, showing the same parts contracted. Fig. 3 is a plan view of a loose leaf binder with the parts in the position shown in Fig. 1, but showing the file posts and tubes broken away. Fig. 4 is a similar view to Fig. 3, but with the parts in the position shown in Fig. 2. Fig. 5 is a longitudinal section taken along the longitudinal axis of the operating screw. Fig. 6 is a transverse section taken at right angles to Fig. 5, through the pivot of one of the wrist plates, and Fig. 7 is a perspective view of a loose leaf binder

showing a modified form of the slide-nut and 55 the link connecting the slide-nut and wrist plates.

Like characters of reference refer to like parts throughout the specification and drawings.

The binder back comprises a middle member *a* and two laterally movable side members *b b'* contained when in their contracted position within the middle member. Mounted in bearings *d* secured to the inner face of 65 the middle member *a* is the operating screw *c*. At the sides of the operating screw *c* are guards *e* extending lengthwise on the inner face of said middle member at each side of said operating screw and projecting above 70 the top thereof. One end of the operating screw extends to the adjacent end of the middle member to receive the turning device *c'* and longitudinally movable on the operating screw between its ends is a slide-nut *f* which 75 may engage the inner faces of the sides, and has flanges *g* which ride on the top, of the guards *e* to prevent the revolution of the slide-nut as its position is altered by the rotation of the operating screw.

Near each end of the middle member *a* is a wrist plate support *h* and pivoted to the wrist plate supports *h* are wrist plates *i* having their pivots *j* on a line parallel with the longitudinal axis of the operating screw. Connected 85 to the wrist plates *i* by pivots *l* is a link *k*.

The inner ends of the links *p p'* are connected to their respective wrist plates *i* by pivots *o'* arranged on lines passing through the wrist plate pivots *j* transversely to the 90 length of the operating screw and the outer ends of the links *p p'* are connected to lugs *q q'* on the inner faces of the side members by pivots *r* arranged on lines passing diametrically through the wrist plate pivots *j* at substantially right angles to the length of the operating screw so that the links may constantly move in parallel planes during the oscillation of the wrist plates and exert their lines of force on the side members at substantially 95 right angles to the length of the screw.

The contracted position of the parts is that shown in Figs. 2 and 4 in which the connecting links *p p'* of each set are in contact with each other across their respective wrist plates. The revolution of the operating screw to open the binder causes the slide-nut 105 to move in the direction indicated by the ar-

row shown in Fig. 4, and this movement of the slide-nut actuates the link k and causes it to oscillate the wrist plates so that they will move the connecting links outwardly in parallel planes to expand the side members of the binder outwardly from the middle member. The links p p' during the outward movement exert their lines of force on the pivots r so that side members will be caused to move outwardly in planes parallel to those of their contracted position. By means of this construction the full power of the operating screw is utilized in expanding and contracting the middle members the contracting movement being merely the reverse of the expanding movement above described.

As shown in Figs. 1 to 6, the link k is pivotally connected to the slide-nut f , by a pin m which causes the link k to move longitudinally 20 on the operating screw in unison with the slide-nut and upon which the link k rocks during the oscillation of the wrist plates as the side members expand and contract.

In Fig. 7, the slide-nut f'' is provided with 25 a slideway f' arranged transversely to the length of the operating screw and the link k'' is formed with a tongue k' which moves in the slideway f' . During the actuation of the slide-nut, shown in Fig. 7, the link k'' causes 30 the oscillation of the wrist plates, and as the pivotal connections of the link with the wrist plates pass the imaginary lines passing through the wrist plate pivots at right angles to the length of the operating screw the 35 wrist plates cause the link k'' to move toward and from the operating screw, and during such movements the tongue and slideway maintain the link k'' constantly parallel with the operating screw.

Having thus fully described my invention 40 what I claim as new and desire to secure by Letters Patent is:

1. A loose leaf binder comprising in its construction a binder back consisting of a middle member and two laterally movable side members located at opposite sides of the middle member, an operating screw mounted in bearings connected to the binder back, two wrist plates pivoted within the binder back, a 45 slide-nut movable on the operating screw, a link actuated by the slide-nut and pivotally connected with the wrist plates whereby it will oscillate them during the movement of the slide-nut, two sets of links pivotally connected to the wrist plates on opposite sides of the wrist plate pivots and pivotally connected to their respective movable side members at substantially right angles to the length of the operating screw whereby the 50 links of each set may move in substantially parallel planes during the oscillation of the wrist plates and during said movement constantly exert their lines of force on said movable side members at substantially right angles to the length of the screw.

2. A loose leaf binder comprising in its construction a binder back consisting of a middle member and two laterally movable side members located at opposite sides of the middle member, an operating screw mounted in 70 bearings connected to the binder back, two wrist plates pivoted within the binder back, a slide-nut movable on the operating screw, a link actuated by the slide-nut and pivotally connected with the wrist plates whereby it will oscillate them during the movement of the slide-nut and two sets of links having their inner ends pivotally connected to the wrist plates on opposite sides of the wrist plate pivots and at the same distance therefrom and having their outer ends pivotally connected to their respective movable side members on lines passing diametrically through the wrist plate pivots at substantially right angles to the length of the operating screw whereby the links of each set may move in substantially parallel planes during the oscillation of the wrist plates and during the said movement constantly exert their lines of force on said movable members at 80 substantially right angles to the length of the screw.

3. A loose leaf binder comprising in its construction a binder back consisting of a middle member and two laterally movable side members located on opposite sides of the middle member, an operating screw operatively mounted in the binder back, two wrist plates pivoted within the binder back, a slide-nut movable on the operating screw, a link actuated by the slide-nut and pivotally connected with the wrist plates whereby it will oscillate them during the movement of the slide-nut and two sets of links pivotally connected to the wrist plates and to their 90 respective movable side members.

4. A loose leaf binder comprising in its construction a binder back consisting of a middle member, and two laterally movable side members located at opposite sides of the middle member, an operating screw mounted in 100 bearings connected to the binder back, two wrist plates pivoted within the binder back, a slide-nut movable on the operating screw, a slide-way in the slide-nut arranged transversely to the length of the operating screw, a link, a tongue for the link slidably contained within the slideway, said link being pivotally connected with the wrist plates whereby it will oscillate them during the movement of the 110 slide-nut on the operating screw, two sets of links pivotally connected to the wrist plates on opposite sides of the wrist plate pivots, and pivotally connected to their respective movable side members at substantially right 115 angles to the length of the operating screw.

5. A loose leaf binder comprising in its construction a binder back, consisting of a middle member, and two laterally movable side members located at opposite sides of the mid- 120

- idle member, an operating screw mounted in bearings connected to the binder back, two wrist plates pivoted within the binder back, guards within the binder back at the sides of the operating screw, a slide-nut movable on the operating screw and engaging the guards, a slideway in the slide-nut transverse to the length of the operating screw, a link, a tongue for the link contained in the slideway where-
5 by the slide-nut can actuate the link during its movement on the operating screw, said link being pivotally connected with the wrist plates whereby it will oscillate them during its movement with the slide-nut, and two sets of links having their inner ends pivotally connected to the wrist plates on opposite sides of the wrist plate pivots and having their outer ends pivotally connected to their respective movable side members. 15
